Patented Nov. 2, 1920.

UNITED STATES PATENT OFFICE.

YUBIE WILLIAM ROGERS, OF ST. LOUIS, MISSOURI.

COMBINATION-CHAIR.

1,357,255.

Specification of Letters Patent. Patented Nov. 2, 1920.

Application filed May 8, 1920. Serial No. 379,979.

To all whom it may concern:

Be it known that I, YUBIE WILLIAM ROGERS, a citizen of the United States, residing at St. Louis, in the State of Missouri, 5 have invented a new and useful Combination-Chair, of which the following is a specification.

My invention relates to improvements in combination chairs in which the back is elevated on hinges to a table top position; and the object of my improvement is to provide a chair of this type, having a right angled back support, pivotally connected to one corner of the seat; with a side panel, having 10 a stirrup like supporting member, rigidly fixed to the said right angled back support. The utility of this mechanism in the chair is to give access to a receptacle beneath its seat, prevent upsetting of the table, when 15 swung from the seat, and by the foot in the stirrup, prevent swinging of the table while in use. I attain these objects by the mechanism illustrated in the accompanying drawing, in which—Figure 1 is a view of the device, when used as an ordinary chair. Fig. 2 is a view of the device, when used as a 20 seat at a table. Fig. 3 is a rear view of the device, showing the mechanism and parts of the right angled back supporting members. Similar numerals refer to similar 25 parts, throughout the 3 views. Numeral 1 is the box seat of the chair, having a right angled back supporting member 2, pivotally connected to one of its rear corners, by means

of hinges 5. A side-panel 3 is rigidly secured 35 to the back support 2 and serves as door to a receptacle beneath the seat of the chair. A stirrup like support 4 is secured to the panel 3, to prevent upsetting of the table, when swung clear of the seat on its hinges 5. 40 Swinging of the table is prevented and adjustment given by a pressure or twist of the foot in the stirrup 4. The back 6 which forms the surface of the table is hinged to the horizontal member of support 2, and is 45 held, when in a table top position, by means of a hinged prop 7, which engages a pin 8 of the vertical member of support 2.

I do not confine myself to the exact arrangements of parts herein shown and described, for many changes may be made in my device, without departing from the nature of my invention.

Having thus described my invention, what I claim is—

In a combination chair, a seat having a hinged back supporting upright to which a side panel is attached; a horizontally disposed member fixed to said upright, a chair back pivotally attached to said horizontal 60 member and adapted to be swung in a horizontal plane from normal vertical position to a horizontal table top position thereabout, means to support the back in its latter position, and means to be engaged by the foot 65 to move and support the said panel in adjusted position; substantially as described.

YUBIE WILLIAM ROGERS.
